UNITED STATES PATENT OFFICE.

MORRIS NEWGOLD, OF NEW YORK, N. Y.

DESIGN FOR A LAMP-BODY.

SPECIFICATION forming part of Design No. 31,712, dated October 24, 1899.

Application filed September 16, 1899. Serial No. 730,778. Term of patent 3½ years.

To all whom it may concern:

Be it known that I, MORRIS NEWGOLD, a citizen of the United States, residing at New York, Manhattan borough, in the county and State of New York, have invented and produced a new and original Design for a Lamp-Body, of which the following is a specification, reference being had to the accompanying drawing, forming part thereof.

- 10 • The figure is a view in perspective of a lamp-body, showing my new design.

As shown in the drawing, the leading or material features of my design are in a general sense the outlines or configurations of a fanciful Saurian reptile or dragon in a crouched or retrieved attitude, the neck portion A thereof being thrown upward and backward, the mouth being fully open, and a nozzle portion B, substantially cylindrical in outline, projecting outward from the latter. The nozzle portion B is shown as formed with spiral ribs and corrugations, and the body proper is shown as formed with numerous minute raised

portions a, indicative of the scales of the reptile. The body proper is further shown as 25 formed with raised irregularly-curved portions, as d and e, together with certain minute raised portions D, the latter indicative of one of the rear feet of the reptile. The tail portion E is curved partially under the body 30 proper of the reptile. At the side of the reptile's body proper is an obliquely-arranged shield C of irregular outline or edge contour, the same indicating one of the wings of the reptile and the stem portion c thereof indicating one of the front feet of the reptile. 35

Having thus described my invention, what I claim as new, and desire to secure by Letters Patent, is—

The design for a lamp-body, substantially 40 as herein shown and described.

MORRIS NEWGOLD.
